BLIND

Henry J. Mackin, Kankakee, Ill.

Application December 20, 1940, Serial No. 370,994

19 Claims. (Cl. 156—17)

This invention relates to a blind of the so-called "Venetian blind" type. It has for one object to provide a blind which is simple in construction and efficient in use. Another object is to provide a blind which may be assembled in or near a window with a minimum of difficulty. A further object is to provide a Venetian blind in which the parts are made separately and so arranged that, when installed, they fit together readily without the necessity of being permanently fastened together, as, for example, by bolts, screws, welding or other means. Another object is to provide a Venetian blind-tilting mechanism.

Other objects will appear from time to time throughout the specification and the claims.

The invention is illustrated more or less diagrammatically in the accompanying drawings, wherein:

Figure 1 is a front elevation from the inside of the blind looking toward a window or opening in which the blind may be positioned. Parts are broken away and parts are in section;

Figure 2 is a transverse horizontal section taken at line 2—2 of Figure 1;

Figure 3 is a vertical section taken at line 3—3 of Figure 1;

Figure 4 is a vertical sectional detail on an enlarged scale showing the shaft-carrying means positioned at the righthand side of Figures 1 and 2. It may be considered as taken at line 4—4 of Figure 2;

Figure 5 is a vertical sectional detail taken at line 5—5 of Figure 1;

Figure 6 is a sectional detail on an enlarged scale, showing the shaft-supporting means and tilting means positioned at the lefthand side of Figures 1 and 2. It may be considered as having been taken at line 6—6 of Figure 2;

Figure 7 is a transverse sectional detail taken at line 7—7 of Figure 1;

Figure 8 is a transverse sectional detail taken at line 8—8 of Figure 6.

Like parts are designated by like characters throughout the specification and the drawings.

While the Venetian blind of this invention may be mounted in many different arrangements, as shown herewith, it is mounted adjacent a window and within the window opening or trim which is indicated diagrammatically by the upper member 1, the lower member 2 and side members 3 and 4. The invention is in no way limited to any particular mounting or to mounting in any particular location.

As shown, a righthand hollow guide member

5 is mounted on the structural member 3. It comprises a generally tubular member of more or less rectangular cross section and is shaped to provide a longitudinal opening or slot 6 which is bounded by the outwardly extending edges 7 formed preferably integrally with the material of the tubular member 5, which edges may be inwardly bent as at 8, if desired. The righthand guide 5 is preferably cut away adjacent its top to provide an opening or door 9, the purpose of which will be described below.

On the opposite or lefthand side of the blind construction is provided a guide member 10 which is generally the same as the member 5. It is slotted longitudinally as at 11, the slot being bounded by the outwardly bent edges 12 of the material which forms the guide 10. They may be rearwardly bent as at 13, if desired. Near its bottom, each of the guides 5 and 10 may be engaged by a saddle-like member 14 which is placed across the lower end of the slots 6 and 11, and whose edges may be bent about the flanges 7 or 12 as at 15, if desired. These yokes are preferably held in place by screws 16 whose heads engage the yokes 14 and which pass through suitable perforations in the guides 5 and 10 and engage the window frame or other structural member 3 or 4 as indicated particularly at 17, 18 in Figure 1. Mounted on each of the screws 16 may be a roller 18 grooved as at 19 for a purpose which will be described below.

A shaft assembly, which will be described more in detail below, is arranged to raise and lower the blind which is to be hung between the guides just described. At one end the shaft is supported in a bearing and means are provided at that end for rotating the shaft. At the other end, the shaft is supported in a second bearing and means are provided at that end for tilting the blind. The driving end of the shaft support will first be described.

As shown in Figures 1 and 2, the blind raising and lowering means are driven at the righthand end. The means for so driving the blind comprise a housing member 20, having a flange 21 along one side, the flange being cut away as at 22 and notched as at 23. At its top, the housing 20 is provided with a relatively larger flange 24 which extends to the right as shown in Figures 2 and 4, and this flange is provided with two downwardly depending ears 25, 25, which are separated from the flange 21 by slots 26, 26. The housing 20 is provided with a generally tubular section 27 within which is formed a ball race 28, within which are mounted ball bearings 29.

An inner ball race 30 is provided and is preferably mounted upon a tubular section 31. A retainer 32 may be used, if desired. The invention is not limited to the use of anti-friction bearings or to any particular form of such bearings when they are used. The bearings shown are merely indicative of the possibility of including anti-friction bearings, if desired. At its inner end, the tubular section 31 has seated upon it a sprocket wheel 33, which may be retained on the tube in any desired manner. As shown, several ears 34 are upset from the section 31 and hold the sprocket 33 in place thereon. The tubular section 31 may be slotted as at 35.

When the parts are to be assembled, the guide 5 being in the position shown in Figures 1, 2 and 3, the housing 20 slides into place, the notches 23 engaging the inward bent edges 8 of the flanges 7, and the ears 25 fitting into the upper open end of the guide 5, the front walls of the guide passing into the slots 26. With the parts thus assembled, a screw 36 may be inserted through the opening 37 in the housing 20, and passing through a suitable corresponding opening in the back of the guide 5 this screw is seated in a portion of the structural member 3, as shown at 38. As a means for covering the opening 9 in the guide member 5, a hood 39 may be used. While this hood may be of many different forms, as shown, it is generally trough-like or U-shaped in cross section; it has a short side 40, a longer side 41 which terminates in an inwardly bent flange 42 which, as shown particularly in Figure 2, is engaged at one side between the flange 7 and the rearwardly bent flange 8 along one side of the opening 6 in the guide 5. This member is held in place by the friction of the parts alone and need not have other fastening.

At its opposite end, the shaft supporting mechanism is, as shown, at the left of Figures 1 and 2 and in detail in Figures 6, 7 and 8. This assembly includes a housing 43 generally similar to the housing 20. It has a flange 44, cut away as at 45, and notched as at 46. It has the extended rearward flange 47 which terminates in downwardly extending ears 48 separated by slots 49 from the flange 44. It may be held in place by a screw 50 which passes through the opening 51 in the housing 43 and extends into the structural member 4 as at 52. Similarly, to the housing 20, it includes a tubular section 53 within which is a ball race 54 in which ball bearings 55 are positioned. An inner ball race 56 is secured to a tubular member 57. A retainer 58 may be used, if desired. At its inner end, generally with the housing 43, the tube 57 has fixed upon it a sprocket 59 which is held in place by a number of ears 60 upset from the end of the tube 57. The tube may be slotted at its opposite end as at 61.

The tubular section 53 may be enlarged as at 62, this enlargement merging into the outer face of the housing 43. A guide flange or projection 63 is formed in the outer face of the housing 43 and one or more guide projections 64 may be formed toward the bottom of the housing 43 and adjacent the enlargement 62 of the tubular member 53. At the point where the tubular member 53 joins the enlargement 62, a shoulder 65 is formed; and against this a generally hollow, tilting worm gear 66 is adapted to fit. The bearing portion 67 of the gear 66 bears upon the outer surface of the tubular member 53 and may bear against the shoulder 75

65. At its inner end, the gear 66 has formed upon it a worm gear 68. The tubular portion of the member 66 is provided with two sets of slots which are arranged as shown, for example, in Figure 7; a lower set of slots 69 and an upper set of slots 70 are also provided. It may also be provided with a longitudinal depression 71. The worm gear and associated parts just described comprise part of the tilting means and are enclosed within a housing 72 which is provided with a flange 73 which engages the guide projections 63 and 64 and is held in place on the housing 43 by one or more screws 74. The flange 73 is thickened as at 75 to provide bearings for the shaft 76 of a worm 77 which is mounted for rotation with a pocket or depression 78. A cord guide includes a hub 79 and a yoke construction 80 and is mounted for rotation about the shaft 76. A cord engaging pulley 81 is secured on the shaft 76 and by means of it the shaft may be rotated. The pulley may, as here shown, be formed of two separate parts fastened together or may be otherwise made. It may be attached to the shaft in any manner desired. As shown, the end of the shaft is riveted over as at 82 to hold the pulley fixed upon it. The housing 72 is shaped to engage a shoulder 83 on the gear 66 to prevent its outward displacement.

30 The two tubular sections above described—namely, the parts 31 and 57—are arranged to receive the ends of a shaft 84 which, as here shown, is fitted at one end into each of the tubular sections and is held against rotation by 35 a cotter pin 85 or 86, which cotter pins engage, respectively, the slots 35 and 61. The shaft might be secured to the tubular sections in any other desired manner.

30 The blind itself comprises an upper tilting rail 40 which, as shown, may be made of metal and includes a partially rounded section 87 which is formed integrally with two flat side portions 88, 89. Adjacent its righthand end, as shown particularly in Figures 1 and 2, the tilting rail has secured within it an attaching member 89 which includes two lateral members or side portions 90, 90, which may be held in place in the rail by set screws 91, 91, which includes also a rounded section 92 which extends preferably somewhat 45 more than 180 degrees. As shown particularly in Figure 1, this section 92 extends into the space between the members 27 and 31 and thus centers and supports the tilting rail with respect to the righthand assembly. At its opposite or lefthand end, the rail extends into the slots 69, 55 69 of the member 66 and, since the member 66 is arranged to be tilted by the rotation of the worm 77, the rail itself is thus adapted to be tilted.

50 Secured to the rail, in any suitable manner, are one or more pairs of tapes 93. These tapes are preferably provided with "ladder" portions 94 which join the tapes of each pair and, thus, each pair of tapes may support a slat 95 upon its "ladder." Preferably, at least two pairs of tapes will be used as shown and there will thus be two "ladder" portions 95 for each slat. The slats as shown are generally flat and may be provided with tongues 96 which pass through the slots 6 and 11 and are thus guided by the guide channel members. The bottom-most slat 97 may, if desired, be made heavier than slats 95 and the tapes may be secured to this slat, if desired. If it is so secured, tacks 98 or other fastening means may be used.

A tilting cord 99, having handles 100, may be positioned about the tilting pulley 81 within the yoke 80, as shown. Movement of the tilting cord in either direction will rotate the pulley 81, the worm 77, the gear 68, and, thus, will tilt the tilting slat 87 and by moving the tapes will tilt the slats.

The weight of the blind, when it is raised, is carried not so much on the tapes as on a bottom-raising or supporting rail 101. As shown, this rail is positioned vertically and extends at each end into the guides 5 and 10. It fits loosely into a shoe member 102 which is provided with ears or lugs 103, 103 which, as shown particularly in Figures 1 and 3, engage that portion of the bottom rail 101 which lies within the guide members 5 and 10 or within the respective flanges of those members or within the slots between the flanges. The shoes 102 are provided with extended guiding and bearing surfaces 104. As shown in Figure 3, one such shoe is positioned so that its guiding surface 104 will contact the inner surface of one side of the guide channel 5. Whether it is in close contact with that member or not is unimportant. It is generally guided and the parts are prevented from turning sufficiently to correct cramping or locking of the parts. Lifting chains 105 and 106 are secured, respectively, to the right and lefthand ends of the lifting rail 101. The chain 105 is positioned about and engages the sprocket 33. Its other or free end passes outward through the opening 9 and extends downwardly as at 107, as shown in Figures 1 and 3. At the opposite or lefthand side the chain 106 engages the sprocket 59. At one end 35 this chain is fastened to the lefthand shoe 102, and at its other end it is fastened to a cord 108 which is positioned about the lefthand roller 18 in its groove 19.

For some purposes and for some uses it is desirable to provide a cover above the tilting rail so that when the latter is in the extreme tilted position the shaft and tape fastenings are covered. For that purpose, a member 109 which may have side flanges 110 is used. At the right-hand end, as shown in Figure 2, it is held in place by the screws 91. At its other end, as shown in Figures 2 and 7, it fits into the notches or slots 70.

As a means for holding the blind in any selected position up or down, a hook 111 is attached to or formed as a part of the guide member 5. As shown in Figures 1 and 3, it is engaged in one of the loops of the chain 107. The weight of the chain and associated parts is such that whenever the chain is released it will automatically engage one of its links upon the hook 111.

I claim:

1. In combination in a Venetian blind, a supporting, guiding and operating structure, including a pair of guide members adapted to be positioned one on each side of said blind, and a pair of housing members, each adapted to be slipped over the upper end of a guide, and a stub shaft in each of said housing members, a sprocket on the inner end of said stub shaft, and a shaft having its ends attached to said stub shafts, a plurality of slats positioned between said guides, a plurality of tapes supporting said slats, a tilting member positioned adjacent said shaft, said tapes being secured thereto, and means for tilting said tilting member to tilt said slats, and a raising bar positioned below said slats, and flexible means secured one at each end of said raising bar, each passing over one of said

sprockets, one of said chains extending outwardly from its housing after passing over its sprocket.

5 2. In combination in a Venetian blind, a supporting, guiding and operating structure, including a pair of guide members adapted to be positioned one on each side of said blind, and a pair of housing members, each adapted to be slipped over the upper end of a guide, and a stub shaft in each of said housing members, a sprocket on the inner end of said stub shaft, and a shaft having its ends attached to said stub shafts, a plurality of slats positioned between said guides, a plurality of tapes supporting said slats, a tilting member positioned adjacent said shaft, said tapes being secured thereto, and means for tilting said tilting member to tilt said slats, and a raising bar positioned below said slats, and flexible means secured one at each end of said raising bar, each passing over one of said sprockets, one of said chains extending outwardly from its housing after passing over its sprocket, said lifting bar provided with a guide shoe at each end, each guide shoe engaging one of said guide members.

10 3. In combination in a Venetian blind, a supporting, guiding and operating structure, including a pair of guide members adapted to be positioned one on each side of said blind, and a pair of housing members, each adapted to be slipped over the upper end of a guide, and a stub shaft in each of said housing members, a sprocket on the inner end of said stub shaft, and a shaft having its ends attached to said stub shafts, a plurality of slats positioned between said guides, said slats having projections entering said guides, a plurality of tapes supporting said slats, a tilting member positioned adjacent said shaft, said tapes being secured thereto, and means for tilting said tilting member to tilt said slats, and a raising bar positioned below said slats, and flexible means secured one at each end of said raising bar, each passing over one of said sprockets, one of said chains extending outwardly from its housing after passing over its sprocket.

15 4. In combination in a Venetian blind, a supporting, guiding and operating structure, including a pair of guide members adapted to be positioned each on each side of said blind, and a pair of housing members, each adapted to be slipped over the upper end of a guide, and a stub shaft in each of said housing members, a sprocket on the inner end of said stub shaft, and a shaft having its ends attached to said stub shafts, a plurality of slats positioned between said guides, a plurality of tapes supporting said slats, a tilting member positioned adjacent said shaft, said tapes being secured thereto, and means carried by one of said first mentioned housings for tilting said tilting member to tilt said slats, and a raising bar positioned below said slats, and flexible means secured one at each end of said raising bar, each passing over one of said sprockets, one of said chains extending outwardly from its housing after passing over its sprocket.

20 5. In combination in a Venetian blind, a supporting, guiding and operating structure, including a pair of guide members adapted to be positioned one on each side of said blind, and a pair of housing members, each adapted to be slipped over the upper end of a guide, and a stub shaft in each of said housing members, a sprocket on the inner end of said stub shaft, and a shaft having its ends attached to said stub shafts and

provided with projections to engage said slots, a plurality of slats positioned between said guides, a plurality of tapes supporting said slats, a tilting member positioned adjacent said shaft, said tapes being secured thereto, and means for tilting said tilting member to tilt said slats, and a raising bar positioned below said slats and extending at each end to one of said guides, and flexible means secured one at each end of said raising bar, each passing over one of said sprockets, one of said chains extending outwardly from its housing after passing over its sprocket.

6. In combination in a Venetian blind, a supporting, guiding and operating structure, including a pair of guide members adapted to be positioned one on each side of said blind, and a pair of housing members, each adapted to be slipped over the upper end of a guide, and a stub shaft in each of said housing members, a sprocket on the inner end of said stub shaft, and a shaft having its ends attached to said stub shafts and provided with projections to engage said slots, a plurality of slats positioned between said guides, a plurality of tapes supporting said slats, a tilting member positioned adjacent said shaft, said tapes being secured thereto, and means for tilting said tilting member to tilt said slats, and a raising bar positioned below said slats and extending at each end to one of said guides, and flexible means secured one at each end of said raising bar, each passing over one of said sprockets, one of said chains extending outwardly from its housing after passing over its sprocket, said lifting bar provided with a guide shoe at each end, each guide shoe engaging one of said guide members.

7. In combination in a Venetian blind, a supporting, guiding and operating structure, including a pair of hollow slotted guide members adapted to be positioned one on each side of said blind, and a pair of housing members, each adapted to be slipped over the open upper end of a guide, and a stub shaft in each of said housing members, a sprocket on the inner end of said stub shaft, and a shaft having its ends attached to said stub shafts, a plurality of slats positioned between said guides, a plurality of tapes supporting said slats, a tilting member positioned adjacent said shaft, said tapes being secured thereto, and means for tilting said tilting member to tilt said slats, and a raising bar positioned below said slats, and flexible means secured one at each end of said raising bar, each passing over one of said sprockets, one of said chains extending outwardly from its housing after passing over its sprocket.

8. In combination in a Venetian blind, a supporting, guiding and operating structure, including a pair of hollow slotted guide members adapted to be positioned one on each side of said blind, and a pair of housing members, each adapted to be slipped over the open upper end of a guide, and a stub shaft in each of said housing members, a sprocket on the inner end of said stub shaft, and a shaft having its ends attached to said stub shafts, a plurality of slats positioned between said guides, a plurality of tapes supporting said slats, a tilting member positioned adjacent said shaft, said tapes being secured thereto, and means for tilting said tilting member to tilt said slats, and a raising bar positioned below said slats, and flexible means secured one at each end of said raising bar, each passing over one of said sprockets, one of said chains extending outwardly from its housing after passing over its sprocket, said lifting bar

provided with a guide shoe at each end, each guide shoe engaging one of said guide members.

9. In combination in a Venetian blind, a supporting, guiding and operating structure, including a pair of hollow slotted guide members adapted to be positioned one on each side of said blind, and a pair of housing members, each adapted to be slipped over the open upper end of a guide, and a stub shaft in each of said housing members, a sprocket on the inner end of said stub shaft and lying within its respective guide member, and a shaft having its ends attached to said stub shafts, a plurality of slats positioned between said guides, a plurality of tapes supporting said slats, a tilting member positioned adjacent said shaft, said tapes being secured thereto, and means carried by one of said first mentioned housings for tilting said tilting member to tilt said slats, and a raising bar positioned below said slats, and flexible means secured one at each end of said raising bar, each passing over one of said sprockets, one of said chains extending outwardly from its housing after passing over its sprocket.

10. In combination in a Venetian blind, a supporting, guiding and operating structure, including a pair of hollow slotted guide members adapted to be positioned one on each side of said blind, and a pair of housing members, each adapted to be slipped over the open upper end of a guide, and a stub shaft in each of said housing members, a sprocket on the inner end of said stub shaft and lying within its respective guide member, and a shaft having its ends attached to said stub shafts, a plurality of slats positioned between said guides, a plurality of tapes supporting said slats, a tilting member positioned adjacent said shaft, said tapes being secured thereto, and means carried by one of said first mentioned housings for tilting said tilting member to tilt said slats, and a raising bar positioned below said slats, and flexible means secured one at each end of said raising bar, each passing over one of said sprockets, one of said chains extending outwardly from its housing after passing over its sprocket, said lifting bar provided with a guide shoe at each end, each guide shoe engaging one of said guide members.

11. In combination in a Venetian blind, a supporting, guiding and operating structure, including a pair of guide members adapted to be positioned one on each side of said blind, and a pair of housing members, each adapted to be slipped over the upper end of a guide, and a stub shaft in each of said housing members, a sprocket on the inner end of said stub shaft, each of said stub shafts being slotted at the end opposite its sprocket, and a shaft having its ends attached to said stub shafts and provided with projections to engage said slots, a plurality of slats positioned between said guides, said slats having projections entering said guides, a plurality of tapes supporting said slats, a tilting member positioned adjacent said shaft, said tapes being secured thereto, and means carried by one of said first mentioned housings for tilting said tilting member to tilt said slats, and a raising bar positioned below said slats and extending at each end to one of said guides, and flexible means secured one at each end of said raising bar, each passing over one of said sprockets, one of said chains extending outwardly from its housing after passing over its sprocket.

12. In combination in a Venetian blind, a supporting, guiding and operating structure, includ-

ing a pair of hollow slotted guide members adapted to be positioned one on each side of said blind, and a pair of housing members, each adapted to be slipped over the open upper end of a guide, and a stub shaft in each of said housing members, a sprocket on the inner end of said stub shaft and lying within its respective guide member, each of said stub shafts being slotted at the end opposite its sprocket, and a shaft having its ends attached to said stub shafts and provided with projections to engage said slots, a plurality of slats positioned between said guides, said slats having projections entering said guides, a plurality of tapes supporting said slats, a tilting member positioned adjacent said shaft, said tapes being secured thereto, and means carried by one of said first mentioned housings for tilting said tilting member to tilt said slats, and a raising bar positioned below said slats and extending at each end to one of said guides, and flexible means secured one at each end of said raising bar, each passing over one of said sprockets, one of said chains extending outwardly from its housing after passing over its sprocket.

13. In combination in a Venetian blind suitable for installation in door and window openings, a pair of lateral hollow channel guide members having longitudinal openings along one side, said guide members being adapted to fit against the inner surface of the opening in which the blind is installed, a tilting and hoisting assembly including a shaft, a tilting member movably mounted adjacent thereto, a pair of housing and bearing members, each housing member having rotatably mounted within it a shaft section carrying a pulley on its inner end in line with its respective guide member, the first mentioned shaft removably engaging said stub shaft sections, and a plurality of slats positioned between said guides, and a plurality of ladder tape members positioned about and supporting said slats, the upper ends of said ladder tapes being secured to said tilting member, and means for tilting said tilting member, and a raising bar positioned below said slats, flexible hoisting means engaged at each end of said raising bar, each hoisting means being passed over one of said pulleys.

14. In combination in a Venetian blind suitable for installation in door and window openings, a pair of lateral hollow channel guide members having longitudinal openings along one side, said guide members being adapted to fit against the inner surface of the opening in which the blind is installed, a tilting and hoisting assembly including a shaft, a tilting member movably mounted adjacent thereto, a pair of housing and bearing members, each adapted to be slidably engaged upon the upper end of one of said guide members, each housing member having rotatably mounted within it a shaft section carrying a pulley on its inner end in line with its respective guide member, the first mentioned shaft removably engaging said stub shaft sections, and a plurality of slats positioned between said guides, and a plurality of ladder tape members positioned about and supporting said slats, the upper ends of said ladder tapes being secured to said tilting member, and means for tilting said tilting member, and a raising bar positioned below said slats, flexible hoisting means engaged at each end of said raising bar, each hoisting means being passed over one of said pulleys.

15. In combination in a Venetian blind suitable for installation in door and window openings, a pair of lateral hollow channel guide mem-

bers having longitudinal openings along one side, said guide members being adapted to fit against the inner surface of the opening in which the blind is installed, a tilting and hoisting assembly including a shaft, a tilting member movably mounted adjacent thereto, a pair of housing and bearing members, said tilting member supported therein, each housing member having rotatably mounted within it a shaft section carrying a pulley on its inner end in line with its respective guide member, the first mentioned shaft removably engaging said stub shaft sections, and a plurality of slats positioned between said guides, and a plurality of ladder tape members positioned about and supporting said slats, the upper ends of said ladder tapes being secured to said tilting member, and a raising bar positioned below said slats, flexible hoisting means engaged at each end of said raising bar, each hoisting means being passed over one of said pulleys.

16. In combination in a Venetian blind suitable for installation in door and window openings, a pair of lateral hollow channel guide members having longitudinal openings along one side, said guide members being adapted to fit against the inner surface of the opening in which the blind is installed, a tilting and hoisting assembly including a shaft, a tilting member movably mounted adjacent thereto, a pair of housing and bearing members, said tilting member supported therein, and each adapted to be slidably engaged upon the upper end of one of said guide members, each housing member having rotatably mounted within it a shaft section carrying a pulley on its inner end in line with its respective guide member, the first mentioned shaft removably engaging said stub shaft sections, and a plurality of slats positioned between said guides, said slats having end projections projecting within the slots in said guides, and a plurality of ladder tape members positioned about and supporting said slats, the upper ends of said ladder tapes being secured to said tilting member, and means for tilting said tilting member, and a raising bar positioned below said slats and having its ends engaged within the slots of said guide, flexible hoisting means engaged at each end of said raising bar, each hoisting means being passed over one of said pulleys, one of said flexible hoisting means extending outwardly from a point above its sprocket to a point of ready engagement for hoisting operation.

17. In a support assembly for Venetian blinds, a plurality of interfitting parts, including two guide members and two housing members slidably fitting one on each guide, and a stub shaft positioned within each housing member for rotation, and a shaft extending between said stub shafts and interfitting with each of them, whereby the stub shafts are connected for simultaneous and equal rotation, and a tilting member, bearing and engaging members secured on said tilting member and interfitting with said housing members.

18. In a support assembly for Venetian blinds, a plurality of interfitting parts, including two guide members and two housing members slidably fitting one on each guide, and a stub shaft positioned within each housing member for rotation, and a shaft extending between said stub shafts and interfitting with each of them, whereby the stub shafts are connected for simultaneous and equal rotation, and a tilting member, bearing and engaging members secured on said tilt-

ing member and interfitting with said housing members, and means on one of said housing members engaging said tilting member and adapted to rotate it.

19. In a support assembly for Venetian blinds, a plurality of interfitting parts, including two guide members and two housing members slidably fitting one on each guide, and a stub shaft positioned within each housing member for rotation, and a shaft extending between said stub

5
10
shafts and interfitting with each of them, whereby the stub shafts are connected for simultaneous and equal rotation, and a tilting member, bearing and engaging members secured on said tilting member and interfitting with said housing members, and a lifting member below said shafts and guided in said guiding members, and flexible hoisting means extending upwardly from said lifting member to and about said stub shafts.

HENRY J. MACKIN.
